UNITED STATES PATENT OFFICE.

ARTHUR C. KELLE, OF CANTON, MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS.

TANK LINING FOR ELECTRIC SWITCHES.

Application filed January 2, 1926. Serial No. 78,828.

This invention relates to the insulation of high tension electrical apparatus, as electric switches, contained in metallic casings or tanks, and particularly rectangular casings, and immersed in the oil or other insulating or arc-quenching fluid contained therein; and has particular reference to insulating linings for said casings.

It is common practice to interpose an insulating lining between the side walls of the enclosing casing and the arcing members of an electric switch to prevent the circuit-interrupting arc from breaking through the oil and coming into contact with the casing, which, usually, is grounded. While the insulating lining may be composed of any suitable insulating material, a lining composed of wood boards joined at their edges to form a box, is desirable for many reasons. The rectangular tanks with which this invention is more particularly concerned are ordinarily formed of heavy sheet iron or steel which is bent into the desired shape to form the flat side and end walls of the casing; and the casing is provided with round corners to increase the strength of the casing.

With the usual wood lining construction, and especially because of the round corners, the lining-box must be made smaller than the casing, and a number, if not all, of the side walls of the lining-box must be spaced from the side walls of the casing. When the switch is opened under heavy load, a considerable pressure may be built up suddenly in the oil, and this pressure is exerted upon the lining-walls. The unsupported lining-walls cannot resist any substantial and suddenly-applied pressure and so often split or crack, thereby uncovering a portion of the casing so that a subsequent arc may attack the casing and burn a hole in it and thereby cause fires, or, at least, a serious disturbance in the switch circuit.

While wood linings are particularly susceptible to the above-enumerated troubles, continuous linings composed of fibre and the like also are subject to the same defects. Consequently an object of this invention is the provision of an insulating casing-

lining so constructed and arranged that it is in direct contact with and so is supported by the strong walls of the casing against rupture due to pressure generated within the casing.

A further object is the provision of a casing-lining so constructed and arranged that its side walls are adapted to lie flat against the side walls of the casing.

A yet further object is the provision of a lining-box composed of side and end boards which are connected to form a completely-insulating enclosure and are arranged to lie flat against the casing-walls.

The side-walls of the casing are adapted to yield under abnormal internal pressures and a further object is to provide a wood lining the side and end boards of which are adapted to be supported by and to yield with the side walls of the casing, without rupturing, and while preserving the insulating-continuity of the lining.

A yet further object is the provision of a casing-lining so arranged that the lining is self-supported against collapse inwardly, and by the casing against collapse in an outward direction.

An additional object of this invention is the provision of a corner construction for sectional linings which will enable the lining-sections to be adjacent to the casing walls at all times and which will allow the sections to flex without rupture and without impairing the efficiency of the lining-insulation at the corners.

A further object is generally to improve the construction of insulating linings for the casings of electrical apparatus.

Fig. 1 is a plan view of a metal tank and an insulating lining constructed according to my invention.

Fig. 2 is a side elevation partly in section of the tank in Fig. 1.

Fig. 3 is an end elevation of the lining box of Fig. 1.

Fig. 4 is a perspective view of a corner locking member of the lining-box.

Fig. 5 is an enlarged detail of a corner construction of a lining box.

Fig. 6 is a view similar to Fig. 5 but 100

illustrating the manner in which the side walls of the lining can yield with their supporting casing walls without rupture and without injuring the insulating capacity of the lining-box.

Fig. 7 is a detail illustrating a spring-member employed for holding the lining in place in the casing.

My invention is particularly adapted for and is here shown as associated with a metal rectangular casing having flat side walls 10 and flat end walls 12, and the round corners 14. The casing lining embodying my invention includes the flat rectangular wood boards 16 which form the side walls of the lining and similar boards 18 which form the end walls of the lining. Said boards are adapted to lie against and in contact with the flat sides of the casing and have widths which are approximately coextensive with the flat sides only of the casing, so that the boards do not extend into or lie upon the rounded corners of the casing. The lining boards are retained in the aforesaid position 20 by means of corner locking members or posts which comprise essentially rectangular strips 20 preferably of wood. V-shaped grooves 22, the side walls of which preferably lie at an angle from 90°, are formed in the opposite edges of said corner posts and extend in parallel relation from end to end of the corner posts. The position and arrangement of said grooves in said corner posts is such that the proximate edges of the side 30 and end boards of the lining are adapted to be received therein with the corner posts disposed at an angle of approximately 45° with both the side and end boards of the lining. As thus arranged, the corner posts bridge the gaps between the side and end boards at the corners of the casing. The similar side faces of the grooves in said corner posts are adapted to terminate at the outer faces 20a of said posts; and the width 40 of such faces is adapted to be about equal to the thickness of the lining boards.

The opposite edges 20b of the corner posts project over the inner faces of the lining boards so that the corner posts may maintain their overlapping relations with the lining boards and so preserve the insulating capacity of the lining.

Preferably the corner posts and lining boards are relatively loosely fitted together 55 whereby to allow for slight variations in dimensions during the fabrication of the tanks and also to give the lining sufficient freedom to enable the component parts of it to flex with the casing.

The lining is self-supporting within the casing and is assembled by sliding the corner posts down between the proximate edges of adjacent side and end boards of the lining. The last corner post inserted serves to lock 65 the lining securely in position.

Spring members 30, Fig. 7, are inserted between the casing and the corner-posts 20, and are adapted to bear against said corner-posts and thereby serve to hold the lining from floating in the oil in the casing.

While I have described my invention in connection with a lining composed of wood boards and wood corner posts, it is obvious that the lining may be similarly constructed of different materials.

I claim:

1. The combination of a casing and an insulating lining therefor, said lining having a plurality of lining-sections and members located between and connecting said sections together, said connecting members constituting supports for said lining-sections against inward movement only and said casing constituting a support for said lining sections against outward movement.

2. An insulating lining for the metal casing of an electrical apparatus, said lining having a plurality of angularly-related flat side walls of insulating material, which side walls are spaced apart at their proximate edges, and corner members disposed between the spaced proximate edges of said side walls and having projections which overlie the inner faces of said side walls and also having projections which engage the end edges of said side walls, the aforesaid projections cooperating to maintain said corner members in position between said side walls, said corner members being free from projections which overlie the outer faces of 100 said side walls, whereby the lining walls are free to move outwardly.

3. The combination of a metal casing having flat side walls and an insulating lining therefor having a plurality of flat side walls 105 of insulating material which lie against the flat side walls of the casing, said insulating flat walls having their proximate edges spaced apart at the corners of the casing, and corner locking members disposed between the proximate spaced ends of said insulating side walls, said corner locking members having opposed parallel longitudinal notches in which proximate edges of said side walls are received and said corner locking members having projections which overlie the inner faces and ends only 115 of said walls, said corner locking members and the projections thereof constituting supports for said insulating side walls 120 against inward movement only and also constituting interlocking connections between said corner members and side walls which permit free and independent outward movements of said side walls.

4. The combination of a casing having flat side walls and round corners and an insulating lining for said side walls composed of boards which lie directly throughout 130 their entire extent upon said side walls and

terminate adjacent but spaced from each other at the round corners, and corner locking posts received in the corners of the casting between the adjacent ends of the boards and having notches in opposite sides which engage the inner faces and ends only of the boards and are free from engagement with the outer faces of said boards, said corner locking members cooperating to hold said

boards against inward movement but imposing no restraint against the outward movement of said boards, so that the boards can move outwardly free from and unrestrained by said corner locking members.

In testimony whereof, I have signed my name to this specification.

ARTHUR C. KELLE.
